UNITED STATES PATENT OFFICE.

WILLIS KNAPP, OF SALT LAKE CITY, UTAH.

FLUID MOTOR.

Application filed March 31, 1921. Serial No. 457,286.

To all whom it may concern:

Be it known that I, WILLIS KNAPP, a citizen of the United States, residing at Salt Lake City, in the county of Salt Lake and State of Utah, have invented a new and useful Improvement in Fluid Motors, of which the following is a specification.

This invention relates to fluid motors for driving rotary tools, or for other purposes, and its object is to simplify and improve the structure whereby a cheaply constructed power means may be constructed, which may be used for a variety of purposes, and which will attain the end in an efficient manner.

In carrying out the invention, there is provided a rotor having paddles so as to constitute a power wheel which is capable of being impelled by water, compressed air, or steam, an inlet duct being provided in tangential relation so as to cause the fluid to strike the blades at an appropriate angle, and a guard or segmental plate lying at one side of and covering some of the blades, whereby fluid entering the casing through the inlet duct is constrained to remain in the portion of the rotor covered by the guard. Provision is also made for mounting the rotor on the intermediate portion of the driving shaft, whereby both ends of the shaft may be utilized for delivering the power created by the wheel, in addition to which the casing containing the rotor is provided with a detachable head, and said head carries the discharge duct for the escape of the fluid after it has acted upon the rotor.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawings:

Fig. 1 is a perspective view of the apparatus.

Fig. 2 is a diametric section of the structure shown in Fig. 1.

Fig. 3 is a face view of the power element, with attachments to the rotor omitted.

Fig. 4 is a view similar to Fig. 3 but show-

ing the inlet to the rotor casing in longitudinal section.

Fig. 5 is a radial section through the power member.

Figure 6 is a sectional view similar to Fig. 2 but on a different radius showing a brush applied thereto.

Referring to the drawings, there is shown in Figs. 1, 2, 3 and 4 and also in others of the figures, a casing 1, preferably of cylindrical contour, although certain parts may be otherwise shaped. The casing or cylinder 1 is provided at one end with a cylindrical or other head 2, constituting a closure for such end of the casing, while at the other end of the casing the latter is open for its full diameter and has external screw-threads 3 permitting the closure of the last named end of the casing by a head 4 which may be screwed onto the casing 1 and formed at one end with a funnel shaped exit 5 to which is secured a duct 6, which duct may constitute a waste duct for fluid entering the cylinder or casing 1 in a manner which will herein-after appear.

Carried by the head end 2 of the casing 1 is an elongated container 7, containing a rotary shaft 8 having a screw-threaded termination 9 extending through a journal bearing 10 in the container 7 and axial to the cylindrical casing 1. The journal bearing 10 forms a stop or abutment for a bevel gear 11 fast to the shaft 8 and meshing with another bevel gear 12, on a countershaft 13 having journal bearings 14, 15 within the container 7, with the countershaft 13 at the end remote from the bevel gear 12, provided with a screw-threaded termination 16, for the reception of another shaft 17, screwed onto the shaft 13 and constituting a shaft through which power may be transmitted from the shaft 8 to some point of utilization of power.

The shaft 8 extends through the head 2, into the casing 1 and there carries a disk 18 with a marginal rim 19 in the form of a flange inset with relation to the periphery of the disk 18, and the disk between the flange 19 and the periphery thereof is provided with a circular series of blades 20 at a sufficient angle to radii of the disk 18 to constitute impeller blades whereby fluid under pressure may be employed to cause rotation of the disk 18, so that such plate with its blades serves the purpose of a propeller or power wheel.

2. Connected to the margin of the casing 1 is a duct 21 in tangential relation thereto and opening through a nozzle 22 into said casing so that fluid travelling through the duct 21 will strike the blades 20 at an appropriate angle to cause the rotation of the propeller in the direction indicated by the arrow in Fig. 8. Within the casing 1, in overlying relation to the blades 20, is a segmental plate or guard 23, whereby fluid entering the casing 1 through the port 22 is constrained to remain in pockets formed by the plate 18, blades 20 and guard 23 for a considerable part of the path of the propeller in its rotation in the casing 1. The structure is such that a material amount of power is imparted to the rotary propeller by fluid under relatively low pressure, such for instance, as may be obtained from a city water system, while higher power may be obtained where air under considerable pressure is available or steam under relatively high pressure is available.
- The shaft 3 has a screw-threaded continuation 24 in line with it but within the casing 1, on the side of the plate 18 remote from the head 2, such threaded continuation 24 being capable of use for carrying certain devices to which reference will herein after be made.
- The duct 21 has interior screw threads 25 at the entering end to receive a threaded coupling 26 on one end of a hose 27, or other means for conveying fluid under pressure, while the other end of the duct 21 is threaded for the reception of a valve 28 conveniently in the form of a pet cock.
- With the structure shown in Figs. 1 to 4, power may be obtained from a source of fluid under pressure through the shaft 17, by directing such fluid under pressure through the hose 27 to act against the blades 20 of the power wheel 18, thus causing the power wheel to rotate and the power to be transmitted through the gears 11 and 12 and the shafts to which they are connected for transmission through the shaft 17 to some point of utilization. The fluid after acting on the power wheel through the blades 20 is discharged into the casing 1, by way of the head 4, neck 5 and duct 6.
- The rotation of the power wheel may also be utilized for various purposes, as for instance, for washing or scrubbing, in the case of an automobile. For this purpose the head 4 is removed from the casing 1 and a rotary brush 80, provided with a head 81 and with bristles 82 on one face of the head, is applied to the threaded shaft extension 24, while a ring 83 is screwed onto the threaded end 3 of the casing 1, such ring carrying a flexible band 84 of rubber cloth or the like designed to engage the surface to be treated by the brush. I do not wish to be limited to the particular use to which the
- motor is applied. For instance, it may be used for generating electricity.
- What is claimed is:
1. In a rotary tool structure, a casing having an outlet, a fluid-driven motor in the casing, an inlet for fluid under pressure entering the casing, and a plate or guard in overlying relation to the rotor and covering a portion of the same adjacent the inlet.
2. In a rotary tool structure, a casing having an outlet, an inlet for fluid under pressure entering the casing, a fluid-driven rotor within the casing consisting of a disk with a marginal rim inset with relation to the periphery of the disk, a series of blades extending from the rim to the periphery of the disk and fixed to both so that the periphery and one side of each of the blades is open, and a plate or guard within the casing in overlying relation to the open side of the blades and adjacent to the inlet, whereby fluid entering the casing is constrained to remain in the portion of the rotor covered by the guard.
3. In a rotary tool structure, a cylindrical casing closed at one end and having an outlet at the other end, a fluid driven rotor in the casing, an inlet for fluid under pressure entering the casing tangentially to the rotor, and means for connecting to the rotor devices to be driven thereby, the rotor having a peripheral series of blades and the casing having a segmental cover for the bladed portion of the rotor defining a fractional portion of a complete rotation of the rotor.
4. In a rotary tool, a casing, a fluid-responsive rotor mounted within the casing, said casing having a closed head adjacent the rotor, another head attachable to and removable from the opposite end of the casing and provided with a discharge duct, and a shaft for the rotor having one end extending from the rotor and terminating within the casing, whereby the removable head may be taken off and that portion of the casing between the rotor and the open end may be utilized to receive an element to be engaged with the end of the shaft and driven by the rotor.
5. In a rotary tool, a casing, a fluid-responsive rotor mounted in the casing, means associated with the casing for delivering fluid under pressure against the rotor to drive it, a shaft for the rotor having one end terminating within the casing and having the other end terminating exterior to the casing, said casing having a removable head which closes an opening in the casing leading to the first-mentioned end of the shaft.
6. In a rotary tool, a casing, a fluid-responsive rotor mounted in the casing, said casing having a closed head adjacent the rotor, another head attachable to and removable from the opposite end of the cas-

ing and provided with a discharge duct, a shaft for the rotor passing through the head, an elongated container carried by and offset from the closed head, a shaft mounted in 5 and projected from one end of the container, and gearing arranged within the container and connecting the two shafts.

7. In a rotary tool, a cylindrical casing, a fluid-responsive rotor mounted in the casing, said casing having a closed head adjacent to the rotor, another head attachable to and removable from the opposite end of the casing and having means for conducting spent fluid therefrom, a shaft for the rotor 10 passing through the closed head and having means at each end for the attachment of devices to be driven by the rotor.

8. In a rotary tool, a cylindrical casing

having a permanently closed head at one end with the other end open and provided 20 with exterior screw-threads, a rotor within the casing adjacent the closed head and responsive to fluid under pressure, a removable head adapted to screw onto the screw-threaded end of the casing and having a 25 duct leading therefrom for conducting spent fluid from the casing, a shaft for the rotor with screw-threads at each end, and gearing on and driven by the rotor shaft 30 and adapted to transmit power to a distant point.

In testimony that I claim the foregoing as my own, I have hereto affixed my signature.

WILLIS KNAPP.
